UNITED STATES PATENT OFFICE.

JOHN SELLERS BANCROFT AND AMOS L. KNIGHT, OF PHILADELPHIA, PENNSYLVANIA,
ASSIGNORS TO LANSTON MONOTYPE MACHINE COMPANY, OF PHILADELPHIA, PENN-
SYLVANIA, A CORPORATION OF VIRGINIA.

MULTIPLE-BLADE TYPE-MOLD.

1,328,256.

Specification of Letters Patent. Patented Jan. 20, 1920.

Application filed June 7, 1918. Serial No. 238,731.

To all whom it may concern:

Be it known that we, JOHN SELLERS BANCROFT and AMOS L. KNIGHT, both citizens of the United States, and residents of Philadelphia, county of Philadelphia, State of Pennsylvania, have invented certain new and useful Improvements in Multiple-Blade Type-Molds; and we do hereby declare the following to be a clear and exact description 10 of the same, reference being had to the accompanying drawings and to the characters of reference marked thereon.

The present invention relates to improvements in type molds, such as those adapted 15 to be used in connection with typesetting machines and has for its general objects to produce a mold capable of casting a variety of type sizes, such a mold being conveniently provided with dimensioning and 20 ejecting mechanism in the form of a plurality of blades, certain of which can be connected for operation while the remaining are locked in closed, inoperative position, the blades preferably being arranged side 25 by side; to produce a mold for casting type composed of portions at right angles to each other, such as type having a vertical body portion and a horizontal face bearing overhang or platform portion, a mold of this kind 30 being provided with dimensioning and ejecting mechanism having action or effect upon both the body and the overhang portion of the type. More specifically the invention has for its purpose to produce an overhang 35 or platform type mold having a main mold blade of type shoulder height and a plurality of supplemental blades slidable on a reduced portion of one of the type blocks of the mold, the supplemental blades aiding in 40 the formation and ejection of the platform part of the type while the main blade is concerned with the formation and ejection of the body of the type. Proper adjustment of the supplemental blades make it possible 45 to produce types of a variety of point sizes, the body portion of the type, however, being unvarying in point size. Further objects and purposes of the present invention will be hereinafter pointed out or will otherwise appear in connection with the following description of the embodiment of the invention shown in the accompanying drawings in which—

Figure 1 is a plan view of a mold illustrative of the invention. 55

Fig. 2 is a vertical section substantially on line 2—2 of Fig. 1.

Fig. 3 is a perspective view of the mold blades and their adjusting devices, certain of the stationary parts of the mold being 60 shown broken away and in section,

Fig. 4 is a vertical section of the mold substantially on line 4—4 of Fig. 1,

Fig. 5 is a detail plan view showing the mold blades and their adjusting devices, a 65 part of the mold blade shoes being broken away.

Fig. 6 is a perspective view showing some 70 of the stationary parts of the mold in separated relation,

Fig. 7 is a vertical cross section substantially on line 7—7 of Fig. 1, and,

Figs. 8 and 9 are perspective views of two sizes of types producible from the mold.

The mold chosen to illustrate an embodiment of the invention is of a type well known as manufactured by Lanston Monotype Machine Company and comprises generally a base block having a nozzle opening 75 for the admission of molten type metal to the mold cavity, a water base and squaring block, stationary type or side blocks forming two side walls of the said cavity, a mold blade movable between said type blocks and forming with its forward end another side 80 wall of said cavity, a cross block movable in a path at right angles to the path of movement of said blade and forming the fourth side wall of the cavity, gate blocks and a jet pusher. 90

A mold of this type is conveniently operated when employed as part of a type casting machine of the kind, for example, disclosed in the United States patent issued to J. Sellers Bancroft, No. 625,998, dated 95 May 30th, 1899. This machine operates the mold blade and the cross block in timed relation to each other and to the casting and other mechanism so that during a cast the cross block is in position to form a wall of 100 the mold cavity and the mold blade is retracted from the cross block a distance equal to the set or width size of the type being cast, while during the ejection of the type by the forward movement of the mold blade 105 the cross block is out of its wall forming

sition and the way is free for the type to be pushed into the type carrier or other device forming a part of the mechanism for discharging the type upon the galley of the machine.

The drawings show a mold of the general kind discussed above and embodying the present invention but they include no part of the casting machine and connections thereof, which, it is to be understood, are required for the successful commercial operation of the mold. The base plate or block 8 is a flat plate adapted to be secured to a suitable casting machine and is provided with a nozzle opening 9 for coöperation with the casting mechanism of said machine. Secured to the top of the base plate along the front edge thereof is the abutment 10 carrying the shoe 11 adjustable by means of the set screws 12. This construction as well as that of the cross block 13 and gate blocks 14, 14', slideable on the base plate and between the shoe 11 and the type blocks to be hereinafter described, and of the gate pusher 15 (Fig. 2) and its cam 16 is similar to that of well known molds and need not be further described here: it will be understood also that the whole mold structure shown has many of the features and characteristics of the structures set forth in prior patents such, as for example, that to Amos L. Knight No. 1,219,956, dated March 20th, 1917, and which will be at once recognized by those skilled in the art.

Also mounted directly on the base plate 8 is the water base and squaring block 17, the general shape of which is best shown in Fig. 6. The upward extensions 17', 17'' of the squaring block 17 form a channel between them in which the small type or side block 18 is located but which it does not completely fill; it leaves a space between it and the extension 17' for the main mold blade as will be described hereinafter.

The small type or side block 18 has a portion 18' adjacent the mold cavity, the height of which is reduced so as to be substantially low quad high and a lower supplemental blade supporting portion 18''; the block is secured to the squaring block 17 and to the base block 8 by screws 19, (Fig. 4) through the bottom of the base block; it is also secured to the extension 17'' of the squaring block by screws 19' (Fig. 4) through screw holes 19'' (Fig. 6) in the squaring and small type blocks. When the screws 19' are drawn tight the type block 18 will be spaced from the extension 17' sufficient to allow of a sliding fit between the block 18 and the extension 17', of the type shoulder high main mold blade 20 the bottom of which slides upon the squaring block 17. The mold blade stop 21 is secured by screws to the side of the extension 17' and has a reduced end projecting into an elongated aper-

ture in the mold blade; the end walls of the aperture are adapted to come into contact with said reduced end of the stop at the extremes of the forward and rearward movements of the mold blade so that the stop 21 serves to limit such movements.

The large type or side block 22 is secured to the squaring block 17 and the base block 8 by screws 23 through the bottom of the base block, and to the extension 17' of the squaring block by screws through the screw holes 24 (Fig. 6) in the squaring block and the said type block. One vertical face of the large type block forms a continuation of the end wall of the extension 17' which contacts with the mold blade 20 and so itself contacts with and guides said blade. Another vertical face of said type block 22, which face is at right angles to the face previously mentioned, is in line with a corresponding face of the small type block 18 and with said last mentioned face forms a guiding slide for the cross block 13. It will now be seen that the mold cavity side walls are formed by the two type blocks, the cross block and the forward end of the mold blade: the jet cavity is located between the mold cavity and the nozzle opening 9 and is formed by walls of the squaring block 17, the two gate blocks 14, 14' and the end of the gate pusher 15.

The large type block 22 is provided with a type shoulder high portion adjacent the cross block, a stepped portion 22' slightly lower than the height of extension 17' (see Fig. 7) and an intermediate portion 22'' the latter serving to support the shoe 25, secured to the step 22'' by screws 26 through the holes 26' (Fig. 6).

Held against lateral movement between the shoe 25, the type block portion 22' and the extension 17' of the squaring block 17, but slideable in a direction at right angles to the blade 20 is the controlling slide or member 27 for the main mold blade 20 and the series of supplemental blades 20^a, 20^b, 20^c, 20^d, 20^e and 20^f. The main blade 20, as shown, is provided with an upper section 20' seated directly upon the lower section of said main blade which, as will be observed, is low quad high. The said upper section acts as the cut-off section of a low quad mold blade construction. The lower section of the main mold blade 20 is provided in its top with an intermediate cut down portion leaving the vertical gaging surface 28 (Fig. 2). The upper section 20' rests upon the top of the lower section and has a downwardly extending portion shorter than the cut down portion referred to and is provided with an elongated aperture, said last mentioned portion engaging with the top surface of the cut down portion of the lower section, leaving a vertical wall to engage with said gaging surface 28. When the

lower blade is moved inwardly, the gaging surface 28 will come against the downwardly extending portion of the upper blade 20' to carry said upper blade with the 5 lower blade to correspondingly vary the size of the upper portion of the mold.

The supplemental blades 20^a, 20^b, 20^c, 20^d, 20^e and 20^f are generally speaking similar in construction to the upper blade 20' described 10 and are arranged side by side in sliding contact with each other and between the side of the upper blade 20' and a lateral guiding portion 28', of the block 18, the said portion bringing the block up to type shoulder 15 height. The forward portions of the supplemental blades are slidable on the top of the reduced portion 18' of the small type block 18 and their apertured, downwardly extending portions are slidable on the top 20 of the lower portion 18" of said block 18. The blade 20^a is slidable against the side of the main mold blade upper section 20'. The blade 20' has a one way or lost motion connection with the blade 20^a in the form of a 25 lug 29 at its rear end which extends laterally to contact with the rear end of the laterally extending lug 29^a on supplemental blade 20^a, the latter blade being shorter in length than the blade 20', by an amount 30 equal to the width of the lug 29: in like manner the blades 20^b, 20^c, 20^d and 20^e have lateral lugs 29^b, 29^c, 29^d and 29^e respectively each blade being shorter than the immediately preceding blade by the width of the 35 overlapping lug of the said preceding blade. The blade 20^f, being the last of the series, is not equipped with a lateral lug: This blade is shorter than blade 20^e by the width of the lug 29^e and the length of this lug is not 40 greater than the thickness of the blade 20^f. It will be seen from the above construction 45 that when the forward ends of all the blades are in alinement their rear lugs will be nested in contact with each other, the lug 29^e being in contact with the rear end of blade 20^f; furthermore, that a forward movement of the main blade, the upper section being moved by contact with the gaging surface 28 of the lower section, will 50 accomplish a forward movement in unison therewith of the supplemental blade 20^a when the lug 29 of the upper section 20' of said main blade has become nested with the lug 29^a of the blade 20^a, and this movement 55 will be communicated to all the other supplemental blades the lugs of which are nested directly or indirectly with said lug 29^a of the supplemental blade 20^a.

The rearward movement of the upper 60 blade 20' and of the supplemental blades is brought about by yieldable means comprising the lever 30 pivoted at the point 31 to the blade controlling member 27, one end of the lever extending into one or more of the 65 elongated apertures provided in the down-

wardly extending portions of the upper and supplemental blades, and the other end being connected by a spring 32 to the post 33 fixed to the member 27. This member is provided also with a locking extension 34 70 including an angular projection 34' (Fig. 5) on its end, said locking extension also projecting into said elongated apertures of the upper and supplemental blades. The locking member 34 projects slightly farther 75 into said apertures than the lever 30 so that when the latter contacts with the rear walls of the apertures of any one or more of the blades, the projection 34' of the locking member 34 at the same time contacts with 80 the forward walls of the apertures of one or more of the succeeding blades in the series, particularly of that blade which is next in the series to the last engaged by the lever 30, to the end that the latter blades are 85 locked in closed, inoperative position. It is to be noted that the construction is such that the projection 34' cannot be entered into the blade apertures except at the time that the 90 said blades are in closed position; the blades 95 not held by the projection 34' either directly or through the nesting lugs but controlled by the lever 30 are opened or driven rearwardly by the force of the spring 32 acting through said lever, which spring at 100 all times tends to maintain in open position the blades controlled by the lever. Because the lever and the locking extension are secured to the same sliding element, the member 27, the lever and the extension are moved 105 in unison when the slide is adjusted; hence, the relation is always preserved of locking against movement blades farther along in the series, than those the movement of which is controlled by the lever 30. 105

In the device shown there are seven blades, counting the main blade as a single blade, as it of course may be without affecting the invention herein, and the mold is capable of producing type of seven different point sizes. In order to insure proper adjustment of the slide member 27, the latter is provided with seven notches 35 each corresponding with a blade: these notches as shown are numbered 12, 18, 24, 30, 36, 42 and 48 because when the slide is positioned with the notch 12 held by the detent 36 to be presently described, the lever 30 and the locking bar 34 are positioned so that all of the blades are held locked in closed position except the 110 main blade which, being 12 points in thickness, makes the mold suitable for producing 12 point type; when the notch 18 is engaged by the detent the lever 30 engages with both the main blade and the supplemental blade 115 20^a so that the two operate in unison, a forward movement of the main blade, due to suitable connections with the mold operating mechanism (not shown) projecting into the aperture 37 (Fig. 2) of the lower section 120 130

of said main blade, causing a similar movement of the supplemental blade 20^a against the yielding opposition of the lever 30 and spring 32 by engagement of the lug 29 of 5 the upper section of the main blade with the lug 29^a of the said supplemental blade, this movement being permitted by the yielding of the spring 32; and the rearward movement of the supplemental blade following 10 that of the main blade but due to the spring 32 and lever 30. The supplemental blade 20^a is six points in thickness so that when this blade is operatively combined with the main 12 point blade the mold is for 18 point type. 15 The next supplemental blade 20^b when combined with the main blade and the supplemental blade 20^a by engaging the detent 36 with the notch 24 produces a 24 point mold since the blade 20^b is 6 points thick. It is to 20 be noted that this is the position of the parts as shown in the drawings. Similarly since 25 the remaining supplemental blades are each 6 point blades, the mold is capable of producing also 30, 36, 42 and 48 point type, as 30 the notches 35 indicate.

The spring detent 36 is pivoted to the large type block 22 at 38 and has a tooth suitably designed to enter one of the notches 35 and hold the slide 27 in adjusted position. 35 A spring 39 serves, as is obvious, yieldably to maintain the tooth in the notch selected. A handle 40 is provided for moving the detent out of engagement with the notched slide so that the latter may be manually positioned. The detent is also provided with a stop projection 41 (Fig. 3) for engaging with the under side of the slide to prevent undue movement of the detent, such, for example, as might bring it into the path of the 40 movement of the cross block 13.

It will be observed that the type formed when only the main blade is operated may be ordinary type while all of the larger sizes are provided with a 12 point body 45 and 45 46 (Figs. 8 and 9) and an overhanging face 50 carrying platform such as that indicated in Figs. 8 and 9 by the characters 47 and 47' respectively, the extent of overhang depending upon the number of supplemental blades operated in conjunction with the main blade.

Since the bottom of the overhanging platform bearing the type face is cast on the top of the portion 18' of the small type block, which portion is low quad high, the thickness of the platform proper is equal to the difference between the type shoulder high and the low quad high measurements. Low quads will, therefore, suitably support the platform when the type is placed in a form for printing, stereotyping and the like. 60

When the blades are assembled the mold blade shoe 42 secured to the large type block 22 by screws 42' and the mold blade shoe 43 secured to the squaring block 17 by screws 65 43' in screw holes 43" (Fig. 6) are posi-

tioned to guide and protect said blades. When the slide member 27 is adjusted so that the lever 30 engages with the last of the series of supplemental blades, the locking projection 34' is of course unnecessary 70 and a recess 44, shown in dotted lines in Figs. 1 and 5, is provided in the shoe 43 to receive it under such conditions. A portion of the projection 34' may extend into said recess also when other portions thereof are 75 locking one or more blades near the end of the series, this being the case because the projection 34' may for strengthening purposes be wider, than the point size of the supplemental blades. 80

It will be understood that various modifications may be made in the mold structure, including the blades and their arrangement and the means for controlling and locking them without departing from the spirit and 85 scope of the invention as set forth by the claims.

We claim:

1. A type mold comprising two type blocks each forming a side wall of the mold 90 cavity, one of said type blocks having a portion adjacent the mold cavity reduced in height, whereby a mold cavity shaped to produce overhang type is formed, a mold blade slidable between said blocks and a supplemental mold blade adapted to be moved in unison with the said mold blade to exert an ejecting action on the overhang portion of the type cast, said supplemental blade being slidable upon said reduced portion of said block.

2. A type mold comprising two type blocks each forming a side wall of the mold cavity, one of said type blocks being type shoulder high adjacent the mold cavity and 105 the second less than type shoulder high adjacent the mold cavity, a type shoulder high mold blade slidably fitted between said blocks and a supplemental mold blade slidably on that portion of the second type block 110 which is less than type shoulder high.

3. A type mold comprising blocks forming walls of the mold cavity, one of said blocks having a portion adjacent the mold cavity reduced in height whereby a mold 115 cavity shaped to produce overhang type is formed, a mold blade slidable between two of said blocks, the end wall of said blade forming a wall of the mold cavity and a supplemental mold blade slidable against 120 the side of said mold blade near the top thereof and slidable also upon the said reduced portion of one of said blocks.

4. A mold for overhang type comprising blocks forming walls of the mold cavity, one 125 of said blocks having a reduced portion adjacent the mold cavity whereby a mold cavity shaped to produce overhang type is formed, a mold blade slidable between two of said blocks, the end wall of said blade 130

forming a wall of the mold cavity, and a supplemental mold blade slidable against the side of said mold blade near the top thereof and also upon the said reduced portion of one of said blocks and a lost motion connection between said mold blade and said supplemental blade to effect forward movement in unison when, during the forward movement of the mold blade, its forward end has become alined with the forward end of the supplemental blade.

5. A mold for overhang type comprising blocks forming walls of the mold cavity, one of said blocks having a reduced portion adjacent the mold cavity whereby a mold cavity shaped to produce overhang type is formed, a mold blade slidable between two of said blocks, the end wall of said blade forming a wall of the mold cavity, and a supplemental mold blade slidable against the side of said mold blade near the top thereof and also upon the reduced portion of said block, a lug being provided on one of the blades for operatively connecting the two blades to cause them to move forwardly in unison when, during the forward movement of the mold blade, its forward end has become alined with the forward end of the supplemental blade.

30 6. A mold for overhang type comprising blocks forming walls of the mold cavity, one of said blocks having a reduced portion adjacent the mold cavity whereby a mold cavity shaped to produce overhang type is formed, a mold blade slidable between two of said blocks, the end wall of said blade forming a wall of the mold cavity, a supplemental mold blade slidable against the side of the said mold blade near the top thereof and also upon the reduced portion of said block, a lug being provided on one of the blades for operatively connecting the two blades to cause the supplemental blade to move toward closed position in unison with the mold blade and yieldable means tending to maintain said supplemental blade in open position.

7. A mold for overhang type comprising blocks forming walls of the mold cavity, one 50 of said blocks having a reduced portion adjacent the mold cavity whereby a mold cavity shaped to produce overhang type is formed, a mold blade slidable between two of said blocks, the end wall of said blade forming a wall of the mold cavity, a supplemental mold blade slidable against the side of the said mold blade near the top thereof and also upon the reduced portion of said block, a lug being provided on one 55 of the blades for operatively connecting the two blades to cause them to move forwardly in unison when, during the forward movement of the mold blade, its forward end has become alined with the forward end of the supplemental blade, and means for yield-

ably opposing the said forward movement of the supplemental blade and for causing the rearward movement of said supplemental blade.

8. A mold for overhang type comprising 70 blocks forming walls of the mold cavity, one of said blocks having a reduced portion adjacent the mold cavity whereby a mold cavity shaped to produce overhang type is formed, a mold blade slidable between two 75 of said blocks, the end wall of said blade forming a wall of the mold cavity, a supplemental mold blade slidable against the side of the said mold blade near the top thereof and also upon the reduced portion of said 80 block having said reduced portion and adjustable means for permitting said supplemental blade to be operated or, as desired, locking it in closed inoperative position.

9. A mold for overhang type comprising 85 blocks forming walls of the mold cavity, one of said blocks having a reduced portion adjacent the mold cavity whereby a mold cavity shaped to produce overhang type is formed, a mold blade slidable between two 90 of said blocks, the end wall of said blade forming a wall of the mold cavity, a supplemental mold blade slidable against the side of the said mold blade near the top thereof and also upon the reduced portion 95 of said block, a lost motion connection between said mold blade and said supplemental blade to cause them to move forward in unison when, during the forward movement of the mold blade, its forward end has become alined with the forward end of the supplemental blade, and means adjustable to maintain the supplemental blade locked in closed position.

10. A mold for overhang type comprising 105 blocks forming walls of the mold cavity, one of said blocks having a reduced portion adjacent the mold cavity whereby a mold cavity shaped to produce overhang type is formed, a mold blade slidable between two 110 of said blocks, the end wall of said blade forming a wall of the mold cavity, a supplemental mold blade slidable against the side of the said mold blade near the top thereof and also upon the reduced portion 115 of said block, a lug on one of the blades for operatively connecting the two blades to cause the supplemental blade to move to closed position in unison with the mold blade, yieldable means tending to maintain 120 said supplemental blade in open position and movable means to maintain said supplemental blade locked in closed position.

11. A mold for overhang type comprising 125 blocks forming walls of the mold cavity, one of said blocks having a reduced portion adjacent the mold cavity whereby a mold cavity shaped to produce overhang type is formed, a mold blade slidable between two 130 of said blocks, the end wall of said blade

- forming a wall of the mold cavity, a supplemental mold blade slidable against the side of the said mold blade near the top thereof and also upon the reduced portion of said 5 block, a lug on one of the blades for operatively connecting the two blades to cause the supplemental blade to move to closed position in unison with the blade and a member slidably adjustable in a direction at substantially right angles to said blades, said member including a lever and spring for yieldably tending to maintain said supplemental blade in open position and a locking projection extending beyond said lever 10 whereby, according to the adjustment, the supplemental blade is yieldably forced to open position by the lever or maintained locked in closed position by the locking projection.
- 15 12. A mold for overhang type comprising blocks forming walls of the mold cavity, one of said blocks having a reduced portion adjacent the mold cavity whereby a mold cavity shaped to produce overhang type is 20 formed, a mold blade slidable between two of said blocks, the end wall of said blade forming a wall of the mold cavity, a supplemental mold blade slidable against the side of the said mold blade near the top 25 thereof and also upon the reduced portion of said block, a lug on one of the blades for operatively connecting the two blades to cause the supplemental blade to move to closed position in unison with the mold 30 blade, a member slidably adjustable in a direction at substantially right angles to said blades, said member including a lever and spring for yieldably tending to maintain said supplemental blade in open position 35 and a locking projection extending beyond said lever whereby, according to the adjustment, the supplemental blade is yieldably forced to open position by the lever or maintained locked in closed position by the locking projection, and a spring detent for holding 40 said slidable member in adjusted position.
- 45 13. A type mold embodying the following instrumentalities, to-wit:—blocks forming walls of the mold cavity, a main mold blade and a plurality of supplemental blades arranged side by side, and adjustable means for effecting the movement of desired supplemental blades in unison with the said 50 main blade, said adjustable means being provided with an extension for locking the other supplemental blades in closed, inoperative position.
- 55 14. A type mold embodying the following instrumentalities, to-wit:—blocks forming walls of the mold cavity, a plurality of mold blades movable to dimension said cavity, yieldable means tending to maintain certain of said blades in open position and means 60 capable of being adjusted to lock certain

of said blades in closed, inoperative position.

15. A type mold embodying the following instrumentalities, to-wit—blocks forming walls of the mold cavity, a main mold blade 70 and a relatively movable supplemental mold blade arranged at one side of said mold blade, and a lost motion connection between said main mold blade and said supplemental blade to cause them to move forward in 75 unison when, during the forward movement of the mold blade, its forward end has become alined with the forward end of the supplemental blade.

16. A type mold embodying the following 80 instrumentalities, to-wit:—type shoulder high side blocks, one of which is provided with a reduced portion adjacent the mold cavity whereby a mold cavity shaped to produce overhang type is formed and a reciprocating dimensioning and type ejecting mechanism comprising a vertical portion 85 slidable between the side blocks, the forward end of said portion forming a wall to dimension and to exert ejecting action 90 against the body of the type produced, and a horizontal portion slidable upon the reduced portion of said type block, the forward end of said horizontal portion forming a wall to dimension and to exert ejecting 95 action against the overhang portion of the type produced.

17. A mold for overhang type comprising blocks forming walls of the mold cavity, one of said blocks having a reduced portion 100 adjacent the mold cavity, whereby a mold cavity shaped to produce overhang type is formed, a mold blade slidable between two of said blocks, the end wall of said blade forming a wall of the mold cavity, and a 105 series of supplemental blades arranged laterally of the mold blade and slidable upon the reduced portion of the block, a lost motion connection between said mold blade and the first of the series of said supplemental blades to cause them to move forward in unison when, during the forward movement of the mold blade, its forward 110 end has become alined with the forward end of said supplemental blade, and a lost motion connection between each of the supplemental blades and the next in the series 115 to cause each to be moved forward in unison with the immediately preceding supplemental blade in the series when the forward 120 end of each supplemental blade has become alined with the forward end of the immediately preceding supplemental blade.

18. A mold for overhang type comprising blocks forming walls of the mold cavity, one of said blocks having a reduced portion adjacent the mold cavity whereby a mold cavity shaped to produce overhang type is formed, a mold blade slidable 125 between two of said blocks, the end wall of 130

- said blade forming a wall of the mold cavity and a series of supplemental blades arranged laterally of the main blade and slideable upon the reduced portion of the block, 5 a lug upon said main blade for operatively connecting it with the first of the series of supplemental blades when, during the forward movement of the main blade, its forward end has become alined with the forward end of said supplemental blade, and 10 a lug on each of the supplemental blades to cause each to be operatively connected with the immediately preceding supplemental blade in the series when the forward end of each supplemental blade has become alined with the forward end of the immediately preceding supplemental blade. 15
19. A mold for overhang type comprising blocks forming walls of the mold cavity, 20 one of said blocks having a reduced portion adjacent the mold cavity whereby a mold cavity shaped to produce overhang type is formed, a mold blade slideable between two of said blocks, the end wall of 25 said blade forming a wall of the mold cavity, a series of supplemental blades arranged laterally of the mold blade and slideable upon the reduced portion of the block, a lost motion connection between said mold blade and the first of the series of said supplemental blades to cause them to move forward in unison when, during the forward movement of the mold blade, its forward end has become alined with the forward end of said supplemental blade, and a lost motion connection between each of the supplemental blades and the next in the series to cause each to be moved forward in unison with the immediately preceding supplemental blade in the series when the forward end of each supplemental blade has become alined with the forward end of the immediately preceding supplemental blade, yielding means tending to maintain certain of said supplemental blades in open position and means capable of being adjusted to maintain the remaining supplemental blades locked in closed position. 30 35 40 45
